HAIR CURLING IMPLEMENT

Arthur H. Madore, Los Angeles, Calif.

Application March 8, 1939, Serial No. 260,531

4 Claims. (Cl. 132—33)

My invention relates to an implement particularly adapted for use in dressing and forming 5 curls in hair and the principal object of my invention is, to provide a relatively simple and efficient implement of the character referred to that combines a comb of novel construction and pins and fingers that are utilized with the comb for the convenient and facile curling of strands of hair, the construction of the device being such 10 as to produce curls of different sizes and shapes.

Further objects of my invention are, to provide 15 a hair dressing and curling comb wherein the comb handle is formed with two or more substantially parallel fingers, said handle being constructed so as to receive one or more sliding fingers or specially formed hair pins that 20 cooperate with the fingers of the comb handle in producing curls of hair and further, to construct the fingers of the comb handle and the separately formed fingers or pins so that, after a curl 25 has been formed the comb and its handle may be withdrawn from the curl and the separately formed pins or fingers left in the curl until it has become dry and set.

A further object of my invention is, to provide 30 a hair curling comb and attachments therefor that may be utilized for forming large or small 35 curls or curls that are substantially oval in cross section and which are generally termed flat curls.

A further object of my invention is, to provide 40 a hair curling and dressing comb that may be utilized for applying conventional "bobbie pins" to 45 curls to hold the same in place when formed, simple and effective means being utilized on the comb for opening the forward ends of the legs of bobbie pins just before they engage the curled hair.

With the foregoing and other objects in view, 50 my invention consists in certain novel features of construction and arrangement of parts that will be hereinafter more fully described and claimed and illustrated in the accompanying drawings in which:

Fig. 1 is a side elevational view of a hair curling 55 comb constructed in accordance with my invention.

Fig. 2 is an enlarged cross section taken on the line 2—2 of Fig. 1.

Fig. 3 is an enlarged cross section taken on the line 3—3 of Fig. 1.

Fig. 4 is a top plan view of the comb with a pair of curl engaging pins mounted for sliding movement on the sides of said comb.

Fig. 5 is an enlarged cross section taken on the line 5—5 of Fig. 4.

Fig. 6 is an enlarged cross section taken on the line 6—6 of Fig. 4.

Fig. 7 is a plan view of one of the pins that is adapted to slide lengthwise on the back and handle of the comb.

Fig. 8 is a plan view of the outer end of a modified form of the comb handle.

Fig. 9 is a vertical section taken on the line 9—9 of Fig. 8.

Fig. 10 is an elevational view of the comb handle and showing a finger or prong arranged for sliding movement on said handle.

Fig. 11 is a cross section taken on the line 11—11 of Fig. 10.

Fig. 12 is a cross section taken on the line 12—12 of Fig. 10.

Fig. 13 is a plan view of a modified form of the comb wherein the handle carries an integral finger or prong and a separately formed finger or prong that is mounted for sliding movement on the handle.

Fig. 14 is an enlarged cross section taken on the line 14—14 of Fig. 13.

Fig. 15 is an enlarged cross section taken on the line 15—15 of Fig. 13.

Fig. 16 is a plan view of a pin having three legs or fingers.

Fig. 17 is a plan view of a further modified form of the curl engaging pin.

Fig. 18 is a plan view of a curl engaging pin having four fingers.

Fig. 19 is a side elevational view of the form of pin illustrated in Fig. 18.

Fig. 20 is a cross section of the form of pin illustrated in Fig. 18 and showing the same applied to a curl.

Fig. 21 is a cross section of a modified form of the comb handle.

Fig. 22 is a perspective view of a tube that is utilized in the formation of relatively large flat 40 curls.

Fig. 23 is a cross section of the tube utilized for producing large flat curls and showing the same associated with the comb handle and a sliding pin.

Fig. 24 is a side elevational view of the form of comb and attachment utilized for opening and applying bobbie pins to curls.

Fig. 25 is an enlarged cross section taken on the line 25—25 of Fig. 24.

Fig. 26 is an enlarged horizontal section taken on the line 26—26 of Fig. 24.

Fig. 27 is a side elevational view partly in section and showing a modified form of the bobbie pin opening and manipulating attachment.

Fig. 23 is a cross section taken on the line 28—28 of Fig. 27.

Referring by numerals to the accompanying drawings and particularly to the construction illustrated in Figs. 1 to 7 inclusive, 10 designates the body or back of a comb which may be formed of hard rubber, composition, light weight metal or the like, and depending from the lower edge of said back is a series of teeth 11. Formed 10 integral with and projecting from one end of the comb back 10 is, a pair of substantially parallel fingers 12 spaced a slight distance apart and the upper portion of the upper finger and the lower portion of the lower finger are rounded 15 as clearly shown in Fig. 2.

The corners between the side faces of these fingers and the lower face of the upper finger and the upper face of the lower finger are cut away to provide substantially L-shaped grooves 20 13 that extend the entire length of said fingers, thus forming ways or channels that are traversed by pins utilized in connection with the comb in curling hair, as will be hereinafter more fully set forth.

25 Formed in both side faces of the comb back 10 and extending from the inner ends of the fingers 12 and the grooves 13 therein toward the end of the comb back, opposite the end that is provided with the fingers 12, are longitudinally 30 disposed grooves 14 that are substantially dovetail shape in cross section and which constitute extensions of the channels formed by the grooves 13.

35 Instead of utilizing grooves 14 that are dovetail shape in cross section, said grooves may be T-shape in cross section as designated by 14a (Fig. 21), or said grooves may be rounded in cross section so that their inner portions are larger in diameter than the width of the slots that are 40 formed in the side faces of the comb back and which communicate with said grooves.

45 Adapted to slide lengthwise on the comb back and the fingers 12 are, pins formed of hard rubber, composition, or light weight metal, which pins may be shaped as illustrated in Figs. 7, 16, and 17.

50 In the form of pin shown in Fig. 7, the pin comprises a solid body portion 15, from one end of which projects a pair of fingers 16, the forward end portions 17 of which diverge in order that a strand of hair curled on the fingers 12 will readily enter the space between said fingers.

55 The opening 18 between the fingers 16 to the rear of their diverging forward ends is in the shape of a long, narrow ellipse, in order to accommodate the strand or lock of hair that is curled on the fingers 12 forming the comb handle.

60 The outer edges of the body 15 and the fingers 16 are of dovetail shape in cross section, as illustrated in Figs. 5 and 6, and as a result of this construction, either edge of the pin may be inserted in the channel formed by the grooves 13 and then moved into the corresponding dovetail 65 grooves 14 in the comb back and, due to the shape of the edges of the pin and the groove 14, the pin will retain its position on the side of the comb body.

70 In Figs. 16 and 17, I have illustrated modified forms of the pins that are adapted to be moved from the comb into curls formed on the bifurcated handle thereof and, in these modified constructions both longitudinal edges of the pins are dovetail shape in order that they may slide into 75 the grooves 14 on the comb back and retain their

positions thereon until moved forwardly along the sides of the bifurcated handle.

The form of pin illustrated in Fig. 16 has a single elongated opening 18a for the accommodation of the curl of hair that is formed on the fingers 12 of the comb and, in the form illustrated in Fig. 17 the pin is formed with parallel portions 18b connected at their forward ends and each portion being provided with an elongated narrow opening 18c for the accommodation of 10 the curls of hair.

In the use of the form of comb and pins just described, the end of a strand or lock of hair is positioned between the fingers 12 that form the comb handle and the comb is now rotated to curl 15 the hair on the fingers 12.

A pin of the form illustrated in Fig. 7 and which was positioned on the side of the comb back 10 by moving the pin lengthwise with one dovetailed edge positioned in the groove 14, is 20 now moved forwardly so that the curl of hair on the fingers 12 passes between the diverging forward ends 17 of the pin and said curl of hair finally occupies the elongated narrow opening 18. When so positioned, the edge of the pin occupies 25 the channel or way formed by the grooves 13 and the handle of the comb may now be readily removed from the pin, leaving the same in the curl. After the curl has become thoroughly dry and set, the pin is removed and the curl is dressed 30 and arranged in the conventional manner.

In Figs. 8 and 9, I have illustrated a form of pin wherein the diverging forward ends 17 of the fingers 16 are provided with short slots 19 and, such construction enables the ends of the 35 fingers 16 to be secured to each other by means of a thread or the like which passes through the slots 19 to tie the ends of the fingers to each other and, as a result the pin may be retained in the curl for a considerable period of time, for 40 instance, over night, thus insuring a thorough setting of the curl.

In Figs. 10, 11, and 12, I have illustrated a modified construction wherein a single pin 20 may be formed of the same material as the comb 45 and its handle and, formed on the side of the rear end portion of this pin is a short longitudinally disposed rib 21 that is dovetail shape in cross section in order that it may enter the groove 14 in the comb back. When this single pin is 50 applied to the comb, the rib 21 is positioned in the end of the groove 14 adjacent the ends of the grooves 13 and thus, the main body of the pin occupies a position immediately adjacent and parallel with the fingers 12 so that in effect, a 55 comb handle comprising three fingers is produced. This construction may be utilized to advantage in forming certain forms of curls.

In the construction illustrated in Figs. 13, 14, and 15, the rear or inner end portion 22 of a 60 finger 23 is formed integral with the side of the comb body 10 adjacent the inner ends of the fingers 12 and, mounted for sliding movement in the groove 14 on the opposite side of the comb back and the grooves 13 that are formed in the 65 fingers 12 is the body portion 24 of a separately formed fingers 25. This construction provides a comb handle portion composed of three integrally connected fingers with which may be combined a fourth sliding finger.

70 In Figs. 18 and 19, I have shown a curl engaging pin, preferably formed of small wire, and which may be used as a holder for curls after they are formed. In this form of pin, a section of wire is bent to form substantially parallel legs 75

26 that are connected at one end by a cross member 27 and, looped around this cross member is the connected end 28 of a pin comprising parallel legs 29. The legs 26 of the wider pin and the legs 29 of the narrower pin are spaced so that the four legs are disposed substantially equal distances apart and thus, when the pin is applied to a curl as illustrated in Fig. 20, the legs 29 of the narrower pin pass through the curl and the legs 26 of the wider pin lie against the outside of said curl. The looped end 28 of the inner pin is arranged to swing or hinge upon the cross member 27 so that the legs of the two pins may be swung apart as shown by dotted lines in Fig. 19.

The legs of both pins may be straight or, as illustrated in Fig. 18, they may be waved or corrugated so as to more effectively engage the curl of hair.

20 In Figs. 22 and 23, I have illustrated a construction for producing relatively large, flat curls or curls that are substantially elliptical in cross section. This arrangement comprises a tube 30, preferably of thin sheet metal, and which is perforated as designated by 31 to permit of circulation of air through the wall of the tube and, this tube is adapted to slide lengthwise upon the fingers 12 forming the comb handle. After the curl has been wound onto the tube, a pin having two fingers of the type illustrated in Fig. 7 is moved from the comb back onto the comb handle, with one leg or finger of the pin disposed inside the tube 30 and the other finger outside the curl of hair on said tube and thus, when the tube carrying the curl and the pin that retains the curl on the tube are removed from the comb handle, a large flat or oval curl is produced (see Fig. 23).

The construction illustrated in Figs. 24 to 28 inclusive is particularly adapted for applying so-called bobbie pins to curls and for separating or opening the forward ends of the legs of said pins as they are moved lengthwise on to the divided handle of the comb to engage the curl thereon. In this device, a substantially oval, open loop 32, preferably formed from sheet metal, is adapted to slide onto and from the fingers 12 that form the comb handle.

Formed integral with the ends of this open loop are parallel arms 33, spaced apart throughout their lengths and, when the loop is positioned on the inner portion of the divided handle of the comb, these arms project alongside the back of the comb, as illustrated in Fig. 24.

Formed integral with the end of the loop that passes over the upper one of the fingers 12 of the comb handle and projecting outwardly therefrom in longitudinal alignment with the space between the arms 33, is a lip 34 that is inclined so that it projects from the end of the loop outwardly away from the sides of the handle forming fingers 12 (see Fig. 26).

The upper outer corner of the other end of the loop and which is directly below the outwardly inclined lip 34, is cut away as designated by 35 in order to prevent the connected ends of the legs of the bobbie pin from passing outwardly through the loop when said pin has been positioned on the curl of hair.

In the use of this particular construction, the straight leg of a bobbie pin is positioned between the arms 33 on the side of the comb body and after a strand or lock of hair has been curled onto the handle forming fingers 12, the pin is moved lengthwise between the arms 33 and, as the forward ends of the legs of the pin pass the

lip 34 they will be spread apart and in such condition they will move lengthwise along the inside and outside of the curl on the divided handle of the comb so as to grip and hold said curl.

When the pin has been applied to the curl, the connected ends of the legs of the pin are positioned immediately to the rear of lip 34 and, by slightly rotating the comb and holding the curl and pin the connected end of the latter will be disengaged from the loop as said connected end passes through the notch 35.

In the modified construction illustrated in Figs. 27 and 28, a tube 36 of thin sheet metal is mounted on the outer faces of the arms 33 and positioned in the rear portion of this tube is an expansive spring 37. The forward end of this spring carries a dished plate 38 that is adapted to receive the connected ends of the legs of the pin and projecting from the edge of this plate is a short finger 39. When a bobbie pin is inserted in the open forward end of tube 36 and moved lengthwise therein, spring 37 will be compressed and, at the limit of the movement of the pin into the tube, the plate 38 will slightly rotate so that the finger 39 will move upward into a notch that is formed in the tube 36 directly above the notch 40 that is formed in the outer portion of the wall of the tube for the accommodation of the outer leg of the pin.

After a strand or lock of hair has been curled onto the finger 12 forming the comb handle, the finger 39 is moved downward out of engagement with notch 40 and, the compressed spring 37 will act to instantly move the pin forwardly through the loop 32 and into engagement with the curl of hair on the comb handle.

The construction just described provides simple and efficient means for very rapidly applying bobbie pins to curls on the handle of the comb and for opening said pins as the forward ends thereof pass lengthwise of the curl.

Thus it will be seen that I have provided a hair curling implement that is relatively simple in construction, inexpensive of manufacture and very effective in performing the functions for which it is intended.

It will be understood that minor changes in the size, form and construction of the various parts of my improved hair curling implement, may be made and substituted for those herein shown and described, without departing from the spirit of my invention, the scope of which is set forth in the appended claims.

I claim as my invention:

1. In a hair curling implement, the combination with a comb body and a bifurcated handle projecting from one end of said comb body, there being grooves formed in one of the side faces of the comb body and in the corresponding face of the bifurcated handle, that portion of the groove in the comb body being substantially dovetail shape in cross section, of a hair pin arranged for sliding movement in said grooves and one of the longitudinal edges of which hair pin is dovetail shape in cross section.

2. In a hair curling implement, a comb body, a pair of spaced fingers projecting from one end of said body and constituting a handle for said comb, a finger formed integral with the body of the comb and occupying a parallel position adjacent said spaced fingers and a finger arranged for sliding movement on the spaced fingers on the opposite side thereof from said integral finger.

3. In a hair curling implement, the combina-

tion with a comb and its handle, which handle is slotted lengthwise, there being grooves formed in the side faces of the handle adjacent the slot therein and there being a longitudinally disposed groove formed in the side face of the body of the comb in longitudinal alignment with the slot in the handle, said groove in the handle being dovetail shape in cross section, of a hair pin provided on one side with a tongue that is dovetail shape in cross section and which is arranged for sliding movement in the grooves formed on the side of the body of the comb and its handle.

4. In a hair curling implement, the combination with a comb and its handle, which comb and handle are provided on one of their side faces with a longitudinally disposed groove, that portion of the groove in the body of the comb being dovetail shape in cross section, of a hair pin having a longitudinally disposed tongue that is dovetail in cross section and which is arranged for sliding movement in the groove on the side of said comb body and its handle. 5 10

ARTHUR H. MADORE.
